UNITED STATES PATENT OFFICE

HAROLD HOWE, OF NEW YORK, N. Y., ASSIGNOR TO HOWE FOLDING FURNITURE, INC.,
OF NEW YORK, N. Y.

FOLDING CHAIR

Application filed May 5, 1931. Serial No. 535,167.

My invention relates to folding chairs and has for its primary object the provision of a novel folding mechanism particularly adaptable for use on chairs, benches, and the like, but which is also applicable generally to folding articles wherein certain surfaces thereof are adapted to be folded with respect to other surfaces thereof.

Folding devices for the seat and legs of chairs, benches, and the like have been many and varied but for the most part have either been of a complicated structural nature and design or else necessitating such modification of chair design and appearance as to leave the market practically open for a folding chair which, when unfolded and ready for use, has the general appearance of an ordinary rigid chair of conventional design but which may be folded to occupy very much less space than such rigid chairs.

The purpose of this invention is to provide such a chair and one whose folding parts are of simple, economical and ingenious design but which are of a character that lends rigidity to the chair and do not detract from the appearance thereof.

The principal feature of the invention is a novel arrangement of links so co-related as to provide a very simple and easily operated positive folding mechanism for the seat and front legs of the chair.

Various objects and advantages by way of details will be apparent as the description proceeds, reference now being had to the figures of the accompanying drawing forming a part of this application and wherein like reference numerals indicate like parts.

In the drawing:

Figure 1 is a side view of a chair embodying my invention, certain parts being broken away and others shown in section for clearness of illustration.

Figure 2 is a bottom plan view of the chair, shown in Figure 1, certain parts being omitted for clearness.

Figure 3 is a front elevation of the chair with the seat and front legs folded against the back.

Figure 4 is a detail sectional view taken

on the line 4—4 of Figure 1, and greatly enlarged.

Figure 5 is a detail bottom plan view of a portion of the slide and locking member.

The front legs of the chair are indicated by the reference characters 1 and 2 and the rear legs thereof by 3 and 4. The rear legs 3 and 4 are extended upwardly beyond the height of the front legs and at a slight rearward angle thereto, as at 5, to provide a back frame, connecting and extending between which is the back rest member 6. The rear legs 3 and 4 are connected below the back frame members 5 by the cross pieces 7 and 8. Front legs 1 and 2 are connected together adjacent their upper ends by the cross piece 9.

The seat member 10 is hinged on its underside and at a point spaced inwardly a short distance from its front edge to the cross piece 9, as by the hinges 11. The seat 10 is provided at its rear corners with rigid bracket members 12 suitably secured thereto and extending upwardly therefrom for pivotal engagement with pins 13 carried by the extensions 5 of the rear legs 3 and 4 just above the seat 10. It will thus be seen that the seat 10 is hinged or pivoted upon the rear legs and frame of the chair and the front legs 1 and 2 are hinged to the underside of the seat 10. Obviously, therefore, when the seat 10 is lifted upwardly said seat and the front legs 1 and 2 are adapted to assume the position shown in dotted lines in Figure 1 directly in front of the back frame 5.

Pivoted to the inner side of each of the front legs 1 and 2 are link members 14 and likewise to each of the rear legs 3 and 4 are pivoted link members 15. The opposite ends of these four link members 14 and 15 are provided with a common pivot pin 16 substantially centrally of the chair seat and at a point directly beneath the same.

The particular arrangement of the links provides a substantially V-shaped bracing structure which effectively serves as a brace against lateral stress and strain to which the seat and legs are subjected to in use.

On the underside of the seat 10 and extending from a point adjacent the rear edge there-

of, forwardly to a point adjacent the center thereof, is suitably secured, as by screws 17, a channel guide member 18 open on its underside. Slidably mounted in this channel guide 18 is a lug or shoe 19 provided with a downwardly extending ear 20 projecting below the opening in the guide 18. The pivot pin 16 passes through this ear 20, whereby the inner ends of the four links 14 and 15 are connected to the shoe 19. This shoe 19 is adapted to slide freely within the channel guide 18 and obviously does so upon raising or lowering the seat 10, as indicated clearly in Figure 1, thus providing a very positive folding means for the front legs 1 and 2 as the seat 10 is moved. Adjacent the inner end of the channel guide there is fixedly provided a stop member 18a positioned within the channel and against which the shoe 19 is adapted to engage when the seat 10 is folded to supporting position. Thus a positive stop is provided for the shoe in this position, which takes the shock and strain or stress to which the shoe is subjected in the direction of the stop.

Means are provided whereby the folding parts may be locked when in the unfolded position shown in Figures 1 and 2 in full lines, whereby to lend rigidity to the chair 30 and prevent inadvertent or accidental folding of the seat and front legs. This locking means comprises an arm 21 pivoted to the underside of the seat 10 as at 22 and provided at its inner end with a hook 23 adapted to engage around the ear 20 of the shoe 19 when the seat is down or in unfolded position. A coil spring 24 secured at one end to the channel guide 18 and at the opposite end to one side of the arm 21 serves to normally urge 40 said arm to locking position. It will be noted with reference to Figure 1 particularly, that this locking arm 21 is offset intermediate its ends so as to underlie the channel guide 18 in order to cooperate with the ear 20.

45 The opposite or forward end of the locking arm 21 extends through a slot or recess 25 provided in the upper edge of the cross piece 9 and is provided at its extreme outer end with a downwardly turned angular finger piece or flange 26 lying immediately under the forward edge of the chair seat where it may be readily reached for manipulation. It will be noted that the recess 25 is longer than the width of the locking arm 50 21 in order that same may be rocked on its pivot sufficiently to permit engagement and disengagement of the hook 23 with respect to the ear 20. A pin 21a is carried by the arm 21 and engaged in the open underside of the channel 18, thus limiting the pivotal movement of said arm.

It is believed that the operation of the device is clear from the foregoing description. If it is desired to fold the chair to the dotted line position, shown in Figure 1, the opera-

tor merely presses upon the finger piece 26 to rock the locking arm 21 on its pivot and raises up on the forward edge of the seat 10. This pivotal movement of the seat 10 causes the shoe 19 to slide rearwardly in the channel 70 guide 18 and of course, as soon as said shoe has moved beyond the hook 23, the pressure upon the locking arm may be released. Continued lifting of the seat 10 causes it to assume the dotted line position adjacent the 75 front of the chair back and because of the pivotal connection with the front legs 1 and 2 with the seat, the same likewise assume a substantially vertical position against the underside of the seat 10. The links 14 and 80 15 cooperate to produce a positive smooth and quick folding action of the seat and front legs as the seat is lifted. Likewise as the seat 10 is lowered to horizontal position, said links serve to slide the shoe 19 forwardly 85 in the channel guide and simultaneously lower the front legs 1 and 2 to seat supporting position. As soon as the ear 20 on the shoe 19 has passed the hook portion 23, the same will snap into locking position directly in 90 the rear thereof whereby a rigid chair seat is provided.

It will be noted that the chair may have the usual and conventional appearance of a rigid chair and yet is foldable to a relatively 95 narrow space for storage.

Of course, changes may be made in details of construction and operation without departing from the spirit and scope of my invention. I do not limit myself, therefore, to 100 the exact structure herein shown and described other than by the appended claims.

I claim:

1. A folding chair comprising a back and rear legs, a seat pivoted thereto, front legs 105 pivoted to said seat, links pivoted at one end to said front and rear legs and converging to a movable element at their opposite ends, and means for guiding the movement of said element.

2. A folding chair comprising a back and rear legs, a seat pivoted thereto, front legs pivoted to said seat, links pivoted at one end to said front and rear legs and converging to a common slidable element at their opposite ends, and means for guiding the sliding movement of said common element.

3. A folding chair comprising a back and rear legs, a seat pivoted thereto, front legs pivoted to said seat, a separate link pivoted 120 at one end to each of said front and rear legs, said links converging inwardly from said legs, a common pivot member for the opposite ends of all of said links, and means on said chair permitting guided sliding movement of said common pivot upon folding and unfolding movement of said front legs and seat.

4. A folding chair comprising a back and rear legs, a seat pivoted thereto, front legs 130

5 pivoted to said seat, links pivoted at one end to said front and rear legs and converging to a common movable pivot at their opposite ends, means for guiding the movement of said common pivot and means to lock said common pivot in one position.

10 5. A folding chair comprising a back and rear legs, a seat pivoted thereto, front legs pivoted to said seat, a separate link pivoted at one end to each of said front and rear legs, said links converging inwardly from said legs, a common pivot member for the opposite ends of all of said links, means on said chair permitting guided sliding movement of said common pivot, and means to releasably lock said common pivot in one position.

15 6. A folding chair comprising a back and rear legs, a seat pivoted thereto, front legs pivoted to said seat, links pivoted at one end to said front and rear legs, said links converging inwardly from said legs, a common pivot member for the opposite ends of all of said links, said member comprising a slidable shoe, and a guide for said shoe on the underside of said seat.

20 7. A folding chair comprising a back and rear legs, a seat pivoted thereto, front legs pivoted to said seat, links pivoted at one end to said front and rear legs, said links converging inwardly from said legs, a common pivot member for the opposite ends of all of said links, said member comprising a slidable shoe, a guide for said shoe on the underside of said seat and a pivoted locking member for releasably securing said member in one position.

25 8. A folding article of furniture comprising a plurality of supporting legs, a seat member having pivotal connection with said legs, a plurality of links each having one end pivoted to one of said legs, and a common pivot for the opposite ends of said links, disposed substantially centrally of said seat.

30 45 9. A folding chair comprising a back and rear legs, a seat pivoted thereto, front legs pivoted to said seat, links pivoted at one end to said front and rear legs and having a common movable pivot at their opposite ends, and means disposed substantially centrally of said seat for guiding the movement of said common pivot.

35 50 10. A folding article of furniture comprising a plurality of supporting legs, a seat member having pivotal connection with said legs, a plurality of links each having one end pivoted to one of said legs, said links converging inwardly from said legs, and a common pivot member for the converging opposite ends of said links disposed substantially centrally of said seat.

In testimony whereof, I affix my signature.
HAROLD HOWE.
